UNITED STATES PATENT OFFICE

150,134

DESIGN FOR A TOASTER

Lurelle Guild, Noroton, Conn., assignor to Westinghouse Electric Corporation, a corporation of Pennsylvania

Application April 5, 1947, Serial No. 138,181

Term of patent 14 years

(Cl. D81—10)

To all whom it may concern:

Be it known that I, Lurelle Guild, a citizen of the United States, residing at Noroton, in the county of Fairfield and State of Connecticut, have invented a new, original, and ornamental Design for a Toaster, of which the following is a specification, reference being had to the accompanying drawing, forming a part thereof.

Fig. 1 is a side perspective view of a toaster embodying my new design;

Fig. 2 is a top plan view thereof;

Fig. 3 is an end elevational view thereof; and

Figs. 4 and 5 are, respectively, fragmentary sectional views taken along the lines IV—IV and V—V of Fig. 2.

The side of the toaster not in view in Fig. 1 is similar in appearance to the side shown. The end of the toaster not in view is similar in ap-

pearance to the end shown except that, the vertical slot and the small circular handle adjacent the bottom thereof, as best shown in Fig. 3, are omitted.

I claim:

The ornamental design for a toaster substantially as shown and described.

LURELLE GUILD.
